(57) **CLAIM**

The ornamental design for an automobile body, as shown and described.

DESCRIPTION

FIG. 1 is a rear perspective view of an automobile body showing our new design.

FIG. 2 is a front perspective view thereof.

FIG. 3 is a right side view thereof.

FIG. 4 is a left side view thereof.

FIG. 5 is a front view thereof; and,

FIG. 6 is a rear view thereof.

It will be understood that the top is plain and unornamental and further that the broken line shown throughout the drawings is for illustration only, forming no part of the claimed design.
